E. N. HESCOCK AND E. F. SMITH.

PORTABLE ELEVATOR.

APPLICATION FILED MAR. 17, 1921.

1,406,861.

Patented Feb. 14, 1922.

UNITED STATES PATENT OFFICE.

ETHAN N. HESCOCK, OF WESTFIELD, AND ERNEST F. SMITH, OF ELIZABETH, NEW JERSEY, ASSIGNEES TO NEW JERSEY FOUNDRY & MACHINE COMPANY, A CORPORATION OF NEW JERSEY.

PORTABLE ELEVATOR.

1,406,861.

Specification of Letters Patent. Patented Feb. 14, 1922.

Original application filed February 16, 1920, Serial No. 358,870. Divided and this application filed March 17, 1921. Serial No. 453,003.

To all whom it may concern:

Be it known that we, ETHAN N. HESCOCK, a citizen of the United States, residing at Westfield, in the county of Union and State 5 of New Jersey, and ERNEST F. SMITH, a citizen of the United States, residing at Elizabeth, in the county of Union and State of New Jersey, have invented certain new and useful Improvements in Portable Ele- 10 vators, of which the following is a specification, taken in connection with the accom- panying drawings.

This application is a division of our co- 15 pending application Ser. No. 358,870, filed Feb. 16, 1920.

Our invention relates to portable elevators and more particularly to means to positively insure that the elevator, when in use, shall be stabilized.

20 Our invention relates also to locking the hoist mechanism. Our invention further relates to automatically operating the locking mechanism and stabilizing means by tilting a portion of the elevator.

25 Our invention further relates to using a portion of the traction means to bring into play either or both the locking and stabilizing mechanism.

Our invention further relates to a cam 30 yoke in combination with a caster wheel and caster wheel fork provided with a swivel pin, and locking mechanism directly cooperating with the swivel pin.

Our invention further relates to certain 35 combinations, sub-combinations and details of construction which will be more fully hereinafter described and pointed out in the claims.

In the accompanying drawings the same 40 reference numerals refer to similar parts in the different figures.

Fig. 1 is a side elevation of our improved portable elevator with certain parts omitted, shown with the hoist mechanism locked;

45 Fig. 2 is a side elevation, similar to Fig. 1, showing the stabilizing means brought into operative position and the hoist mechanism unlocked;

Fig. 3 is a detail rear elevation on the line

3-3 of Fig. 1, looking in the direction of 50 the arrows;

Fig. 4 is a vertical detail section on the line 4-4 of Figs. 1 and 5, looking in the direction of the arrows;

Fig. 5 is a side elevation of another modi- 55 fied form of our invention;

Fig. 6 is a fragmentary side elevation of still another form of our invention;

Fig. 7 is a perspective view of the catch 60 for holding the handle. 60

It is well known that one of the chief objections to portable elevators is that they are not stable or rigid when in operation. These portable elevators must be easily movable from place to place in the warehouse, factory, dock or other place where they are used. By our invention, without lessening the mobility of the movable elevator, or increasing its weight, we positively insure 65 that it will be stable when the hoist mechanism is operated to lift the load. It is, of course, understood that a comparatively small movement or oscillation at the base or carriage will be greatly multiplied as the platform is raised. Such a wobbling or os- 70 cillation, when the platform is in its raised position is extremely dangerous as the load is apt to tip or fall off the platform with serious injury to the workmen, and possible danger or injury to the load, depending upon 80 the character of the goods being stacked or raised at that time. 75

By our invention we absolutely eliminate all such oscillation or wobbling of the plat- 85 form or of the elevator while the hoisting mechanism is being operated.

Our elevator comprises the usual carriage 1, having the usual traction wheels, not shown, but illustrated in our companion case, and a caster wheel 3. This caster wheel 90 permits ready handling and manipulation of the movable elevator in restricted pas- sages or other locations in which it is used. We also employ a vertical upright 4, the usual winding drum, and movable platform 95 (not shown), crank 5 and gear wheels 6, 7, 8, 9. The winding drum (not shown) is preferably mounted upon the shaft 10 of the

gear wheel 9. The gears, movable platform, and winding drum may be of any approved construction.

To prevent the oscillation or wobbling of the elevator with the consequent danger to the workmen and the load we provide the elevator with any suitable stabilizing means. Various forms of stabilizing means may be employed. We have shown the carriage 1 provided with feet or legs 11, 11 one at each forward end of the carriage 1. By our invention we insure that the tilting of a portion of the elevator will automatically operate the stabilizing means to bring them into their operative or inoperative position as the case may be.

We tilt the carriage 1 by aid of the traction means. Preferably we form a rigid bracket 12 on the vertical upright 4 and through this bracket passes a swivel pin 13 of the caster wheel form 14 which fork is mounted upon the axle 15. The cam yoke 16 is also mounted upon the axle 15 and straddles the caster wheel fork 14. In this cam yoke 16, the radius from the axle 15 to the point 17 is greater than the radius from the axle 15 to the point 18.

When the parts are in the position shown in Fig. 1, the cam yoke has lifted the bracket 12, and with it the front end of the carriage, thereby tilting the elevator and freeing the stabilizing feet 11, 11 from contact with the floor 19. In this position of the parts the elevator can be moved around the floor by pulling upon the handle 20.

Having reached the new position on the floor of the dock, warehouse or wherever it is desired to use the elevator, the handle 20 is swung up to engage with the catch 21 mounted on the upright 4. This will cause the wedge or cam surface 22 on the cam yoke to be forced under the fixed bracket 12, forcing the bracket 12 to assume the position shown in Fig. 2. As the bracket 12 moves down the cam surface 22 the elevator is tilted so that the stabilizing feet 11, 11 (only one being shown) are brought into contact with the floor 19. This insures that the elevator will be supported in a manner that will prevent tilting or oscillation and therefore make the elevator stable, so that a load may be raised and lowered upon the movable platform (not shown) without danger to the workmen or damage to the goods that may be lifted.

To make the elevator "fool proof" so that it cannot be operated to raise or lower the movable platform without first stabilizing the elevator we use some form of locking mechanism, cooperating with the hoist mechanism. This locking mechanism normally locks the hoist mechanism and insures that it cannot be operated until the elevator has been stabilized.

In this form of our invention, we operate

the locking mechanism by means of the swivel pin 13. Various forms of locking mechanism may be used. We have shown different modifications but it is to be distinctly understood that our invention is not to be confined to the particular forms shown in our application by way of example.

In Figs. 1, 2 and 3, we mount a pawl 23 on the housing 24 by means of the pin 25, one end 26 of the pawl being brought over the swivel pin 13, the other end 27 being bent and provided with a tooth to engage with the teeth of the gear wheel 9. A spring 28 normally holds the end 27 of the pawl in contact with the gear wheel 11, thereby normally locking the hoist mechanism, Fig. 1.

When the movable elevator has been brought into position where it is desired to operate the hoist mechanism, this mechanism cannot be operated until the end 27 of the pawl 23 has been disengaged from the gear wheel 9. To do this, however, it is necessary to bring the handle 20 from the position shown in Fig. 1, to that shown in Fig. 2; but in doing this the stabilizing means 11, 11 have to be first brought into contact with the floor 19, thereby stabilizing the elevator, and preventing it wobbling or moving as the movable platform is raised or lowered. The pawl 23 being pivoted to the frame of the elevator moves with it as the frame is tilted. The end 26 of this pawl 23 contacting with the swivel pin 13 will cause the pawl as the frame rocks, to pivot upon the pivot 25 and compress the spring 28, thereby releasing the other end 27 of the pawl from the gear wheel 9, Fig. 2. The handle 20 is preferably secured in the vertical position shown in Fig. 2 by any suitable means, as for example the catch 21.

To move the elevator into a new location the handle is brought back into the position shown in Fig. 1, which will again cause the hoist mechanism to be locked.

We have shown a little different arrangement of our invention in Fig. 5 in which the swivel pin 13 cooperates with an arm 29 on the rod 30, carried in bearings 31, 31 on the frame 4. The upper end of this rod 30 contacts with one end 32 of the pivoted pawl 40, the other end 33 of the pivoted pawl engaging with the teeth on the gear wheel 7. The spring 34 serves to normally press the end 33 of the pawl into contact with the gear wheel 7.

We have also shown another modification of our invention in Fig. 6 wherein the swivel pin 13 cooperates with an arm 35 upon the rod 36, the other end of the rod being provided with rigid arm 37, which is normally pressed into engagement with the gear wheel 7 by means of the spring 38. The operation of the devices shown in Figs. 5 and 6, is similar to that shown in Figs. 1 and 2, in that the locking mechanism locks the hoist

mechanism until the elevator has been stabilized by bringing the feet 11, 11 in contact with the floor 19 of the warehouse, pier or other locality where the elevator is used.

5 Having thus described this invention in connection with illustrative embodiments thereof, to the details of which we do not desire to be limited, what is claimed as new and what is desired to secure by Letters

10 Patent is set forth in the appended claims.

What we claim is:-

1. In a portable elevator the combination of hoisting mechanism, a locking mechanism for said hoisting mechanism, a swivel pin for 15 a caster wheel, a caster wheel, means to tilt said elevator, said swivel pin cooperating with said locking mechanism.

2. In a portable elevator the combination of hoisting mechanism, a locking mechanism 20 for said hoisting mechanism, stabilizing means, a swivel pin for a caster wheel, a caster wheel, means to tilt said elevator, said swivel pin cooperating with said locking mechanism.

25 3. In a portable elevator the combination of hoisting mechanism, a lock for said hoisting mechanism, traction means, including a swivel pin, said pin cooperating with the locking mechanism.

30 4. In a portable elevator the combination of stabilizing means, hoisting mechanism, a lock for said hoisting mechanism, traction means including a swivel pin, said pin cooperating with the locking mechanism.

35 5. In a portable elevator the combination of hoisting mechanism, a lock for said hoisting mechanism, traction means including a swivel pin, said pin cooperating with the locking mechanism and means to raise and

40 lower the elevator.

6. In a portable elevator the combination of hoisting mechanism, traction means in-

cluding a swivel pin, and a locking mechanism in contact with said pin and adapted to be operated by it.

45

7. In a portable elevator the combination of hoist mechanism, a caster wheel, a caster wheel fork provided with a swivel pin, a pawl to lock the hoist mechanism, said pawl cooperating with said swivel pin, and means 50 to tilt a portion of the elevator to operate the pawl.

8. In a portable elevator the combination of hoist mechanism, stabilizing means, a caster wheel, a caster wheel fork provided with 55 a swivel pin, a pawl to lock the hoist mechanism, said pawl cooperating with said swivel pin, and means to tilt a portion of the elevator to operate the pawl and the stabilizing means.

60

9. In a portable elevator the combination of a hoisting mechanism, a locking mechanism for said hoisting mechanism, a swivel pin for a caster wheel, a caster wheel, a caster wheel yoke having a cam or inclined surface, a member on the elevator to cooperate with said cam or inclined surface, said swivel pin cooperating with said locking mechanism.

65

10. In a portable elevator, the combination of hoisting mechanism, traction means including a caster wheel, an inclined or cam member operating in a vertical plane and operated by the traction means, and stabilizing means controlled by the vertical movement of the inclined or cam member, locking mechanism to lock the hoist mechanism, said locking mechanism being controlled by the traction means.
